(57) **CLAIM**

The ornamental design for a packaging for food, as shown and described.

DESCRIPTION

FIG. 1 is a perspective view from above and the front of a packaging for food showing my new design;

FIG. 2 is an end view of the packaging for food as seen from left-hand end in FIG. 3, the right-hand end view being a mirror image thereof;

FIG. 3 is a perspective view from below and the front of the packaging for food;

FIG. 4 is a bottom view of the packaging for food;

FIG. 5 is a side view from the rear of the packaging for food; and,

FIG. 6 is a top view of the packaging for food.

1 Claim, 2 Drawing Sheets
